CLAIM

The ornamental design for a sleeve device, as shown and described.

DESCRIPTION

FIG. 1 is a side view of the sleeve device.

FIG. 2 is a top perspective view of the sleeve device.

FIG. 3 is a bottom perspective view of the sleeve device.

FIG. 4 is a top view of the sleeve device; and,

FIG. 5 is a bottom view of the sleeve device.

The evenly broken lines in the drawings illustrate features that form no part of the claimed design. The dash-dotted lines represent the boundaries of the claim and form no part of the claimed design.
